DESIGN FOR A FLASHLIGHT FOR THEATERS

Edgar V. Gray, Brightwaters, N. Y.

Application February 26, 1940, Serial No. 90,535

Term of patent 14 years

To all whom it may concern:

Be it known that I, Edgar V. Gray, a citizen of the United States and a resident of Brightwaters, county of Suffolk, State of New York, have invented a new, original, and ornamental Design for a Flashlight for Theaters, of which the following is a specification, reference being had to the accompanying drawing, forming part hereof, and in which:

The portion of the flashlight intermediate the end members is square in cross-section.

I claim:

The ornamental design for a flashlight for theaters, as shown and described.

EDGAR V. GRAY.
